MATTRESS FOR BEDS

Albert M. Bank, Jersey City, N. J., assignor to
Sylvia Bank, Jersey City, N. J.

Application June 17, 1936, Serial No. 85,658

17 Claims. (Cl. 5—345)

This invention relates to mattresses for beds and the like articles.

An object of this invention is to provide a mattress of the character described, having improved means to facilitate handling of the mattress, for example, as when turning the same over, including handles normally held against the side of the mattress so as not to protrude any substantial distance therefrom, and the construction being such that the sides of the mattress are yieldingly held against bulging when weight is imposed on the mattress.

Another object of this invention is to provide in a mattress of the character described, highly improved handles which although normally held against the sides of the mattress may nevertheless be easily engaged by the hands for turning or otherwise moving the mattress.

A further object of this invention is to provide a neat and durable mattress construction of the character described which shall be relatively inexpensive to manufacture, easy to use and yet practical and efficient to a high degree.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which is shown one of the various possible illustrative embodiments of this invention,

Fig. 1 is a perspective view of the mattress embodying the invention with parts broken away to show the interior construction;

Fig. 2 is a cross-sectional view taken on line 2—2 of Fig. 1;

Fig. 3 is a partial cross-sectional view taken on line 3—3 of Fig. 2;

Fig. 4 is an enlarged top plan view of the spring element forming part of my improved handle structure;

Fig. 5 is a partial horizontal cross-sectional view through a portion of a side wall of a spring mattress illustrating a handle embodying another form of the invention;

Fig. 6 is a cross-sectional view taken on line 6—6 of Fig. 5;

Fig. 7 is a view similar to Fig. 5, but illustrating still another modified construction; and

Fig. 8 is a cross-sectional view taken on line 8—8 of Fig. 7.

Referring now in detail to the drawings, 10

designates a mattress embodying the invention. The mattress may be of any suitable or usual construction, but is here shown for the purpose of illustration only in the form of an inner spring mattress having padded bottom and top walls 12 and padded side walls 13. Within the interior of the mattress are a plurality of suitably spaced rows of helical coil compression springs 15. Springs 15 may be of generally cylindrical shape or, as shown in the drawings, of the hour glass shape, being of less diameter at the middle than at the ends. The side walls 13, as well as the end walls and top and bottom walls have outer cloth covering portions 17 and inner cloth portions 18 between which is interposed a padding material 19.

The mattress 10 may be provided with a plurality of sets of aligned handles 21, the drawings show, for the purpose of illustration, three such sets of handles, although any suitable number of the same may be employed. Each set of handles consists of a pair of aligned handles on the opposite side walls of the mattress interconnected by means extending through the interior of the mattress as will appear in detail hereinafter.

To accommodate the handles, each side wall 13 of the mattress is provided with a plurality of pairs of spaced eyelets 22 extending through said walls and forming through openings for the purpose presently to appear. Each pair of eyelets 22 on one side wall is aligned with another corresponding pair of eyelets on the other side wall.

The handles 21 may be made of round wire stock or any other suitable strip material; and each has a portion 24 parallel to the side wall of the mattress and from the ends whereof there extends inwardly-bent portions 25 forming shoulders engaging the eyelets 22. Extending from the portions 25 of each handle is a pair of parallel portions 26 disposed substantially at right angles to portion 24 and passing through a pair of eyelets. Portions 26 may be formed with extensions 27 within the mattress terminating in eyes 28 preferably registering with one another. The handles 21, it will now be understood, may be moved relatively to the wall 13, the portions 26 sliding within the eyelets during such movement. When the handles 21 are moved inwardly, the shoulders contact the eyelets to limit such movement.

As shown in the drawings, each aligned pair of handles 21 is connected to a spring cage 30 disposed within the mattress and between springs 15, by a pair of connecting rods 31. The spring cage 30 comprises a helical coil compression

spring 34. Within said spring are a pair of substantially similar oppositely disposed U-shaped members 35. Each member 35 comprises a pair of parallel arms 36 interconnected at one end by a semi-circular portion 37, the outer ends of the arms having outwardly curved hooked portions 38. The hooked portions 38 of one U-shaped member 35 engage one end of the spring 34, whereas the hooked portions 38 of the other U-shaped member 35 engage the opposite end of said spring. The arms extend through the coil spring and the portions 37 of said members 35 project beyond the ends of the spring 34 even when the spring is under no compression.

15 Each connecting rod 31 has eyes 40 and 41 at the ends thereof. One eye engages a portion 37 of one of the members 35, and the other eye engages within the registering eyes 28 on one of the handles. Normally the spring 34 pressing outwardly on the hooked portions 38 causes the portions 37 of the members 35 to be moved toward each other, thus pulling the handles 21 toward each other, to seat the shoulders 25 on the eyelets 22 and hold the handles close to the sides 25 of the mattress.

The spring 34 is preferably under some compression when the handles are engaged with the eyelets so as to hold the sides of the mattress against bulging. Should a weight be placed on 30 the mattress the handles being resiliently interconnected, will hold the sides of the mattress against outward bulging. When it is desired to turn the mattress or lift or move the same, the fingers may be inserted between the portions 24 35 of the handles and the side walls of the mattress, the handles then pulled outwardly compressing the spring 34. As soon as the handles are released, the spring 34 will expand and again draw the handles inwardly against the sides of the 40 mattress.

In Figs. 5 and 6 there is shown a side wall 13a of a mattress 10a similar to mattress 10. Each side wall 13a has a plurality of sets of eyelets, one such set being shown on the drawings. 45 Each set of eyelets comprises a central eyelet 50 and eyelets 51 on opposite sides thereof. Slidably mounted within said eyelets is a handle member 52 of round wire stock or any other suitable strip metal, and having a central looped or folded portion 52a slidably extending through the eyelet 50. Extending from said portion 52a in opposite directions are aligned portions 53 from which there extends inwardly, parallel guide portions 54 slidably passing through the eyelets 51. Received on said looped portion and disposed on the 50 inside of the side wall 13a of the mattress, is a plate 56 having a central slot 57 through which said looped portion passes. Said plate also has openings 58 to receive the parallel portions 54. 60 The plate 56 serves as a stop to limit outward movement of the handle, as for example, when the portions 53 are grasped. Engaging the curved portion of the looped portion 52a is a connecting rod 31a similar to the connecting rod 31 of Fig. 3 and connected to a spring cage 30 likewise similar to that shown in Fig. 3.

It will now be understood that a spring cage interconnects each pair of handles on opposite sides of the mattress. A suitable number of pairs 70 of handles interconnected by the spring cages 30 may be provided for each mattress.

The handle 52 shown in Fig. 5 may be constructed with the parallel portions 54 omitted, in which event the eyelets 58 would also be omitted. With such construction there would be

substituted for plate 56, a washer with a slot to receive the portion 52a. It will be noted that with such construction only one central eyelet is employed and the handle 52 would have oppositely extending end portions which may be grasped by the fingers. 5

In Figs. 7 and 8 there is shown a still further modified form of handle forming part of my invention. The handle 10b shown in said figures, comprises a tubular member 60 of curved cross-section, made of a single piece of flat sheet metal. Said member 60 is provided with contacting apertured ears 61 at the middle, receiving one end of a rod 31b similar to the rod 31 of Fig. 3, and connected to a spring cage 30 similar to the one 15 shown in said figure. The tubular member 60 has outwardly flaring end portions 65 and extending through said tube is a cord 66, the outer ends whereof pass through spaced eyelets 68 on the side wall 13b of a mattress. On the outer side 20 of the wall 13c, is a plate 70, having openings 71 registering with the eyelets and receiving the ends of the cord therethrough. The ends of the cord are knotted as at 73, the knots engaging the plate. 25

If it is desired to move the mattress or turn the same, the fingers may be inserted between the plate 20 and the side wall of the mattress, and the handle then pulled.

It will be noted that the means which interconnects the handles 21, 52 or 10b is extensible only to a limited degree or a predetermined distance. When the spring 34 has been fully compressed due to outward pull on the handles from non-projecting to projecting position, the elastic 35 or yielding connecting means becomes a non-extensible, non-elastic, or positive tie between the handles. When the mattress is lifted by holding the handles, said handles do not bulge the sides 40 of the mattress outwardly because the pull between the handles is taken up by the interconnecting means which limits movement of the handles away from one another.

The spring 34 holds the handles in non-projecting position, as shown in Figs. 3, 5 and 7 of 45 the drawings. When the handles are engaged, the spring permits the handles to be separated so that they may be grasped without pulling outwardly on the sides of the mattress. When the handles are released, the spring pulls the handles 50 inwardly to normal or non-projecting position.

It will thus be seen that there is provided a device in which the several objects of this invention are achieved, and which is well adapted to meet the conditions of practical use. 55

As various possible embodiments might be made of the above invention, and as various changes might be made in the embodiments above set forth, it is to be understood that all matter 60 herein set forth or shown in the accompanying drawings is to be interpreted as illustrative and not in a limiting sense.

Having thus described my invention, I claim as new my desire to secure by Letters Patent: 65

1. In combination with a mattress, means extensible a predetermined distance, and disposed within said mattress interconnecting a pair of opposite walls of the mattress, said means including handles at the side walls of the mattress, 70 and movable toward and away from said walls, and elastic means to yieldingly resist separation of said handles and to hold said side walls against bulging.

2. A mattress having a pair of opposite walls, 75

- 5 a pair of aligned handles on said walls, and means interconnecting said handles, said means comprising a coil spring, and means connecting said handles and spring for compressing said 5 spring upon pulling outwardly on said handles.
- 10 3. A mattress having a pair of opposite walls each provided with a pair of spaced eyelets, the eyelets on one wall being aligned with the eyelets of the other wall, a pair of similar symmetrically disposed handles on said walls, each handle having a pair of parallel portions extending through a pair of said eyelets and a portion interconnecting said parallel portions and disposed on the outside of the mattress, and means in said 15 mattress interconnecting said handles, said means including a coil spring, and means connecting said handles with said spring for compressing said spring upon pulling outwardly on said handles.
- 20 4. An inner spring mattress having padded side walls and coil compression springs between said side walls, each pair of side walls being provided with a pair of spaced eyelets, the eyelets on one wall being aligned with the eyelets of the other 25 wall, a handle on each side wall, each handle having a portion parallel to said side wall, inwardly curved portions on the end of said first portion forming shoulders adapted to engage a pair of eyelets, a pair of portions extending from said 30 inwardly curved portions and passing through said pair of eyelets, a coil spring within said mattress and disposed between the first mentioned springs, and means for connecting said last mentioned spring with said handles.
- 35 5. A mattress having a pair of opposite walls, each wall being formed with a pair of openings, the openings in one wall being aligned with the openings in the other wall, a handle on each wall having a pair of portions passing through a pair 40 of said pair of openings, and a portion interconnecting said pair of portions, and means within said mattress, extensible a predetermined distance, interconnecting said handles, to permit said handles to be pulled apart to a limited degree, and spring means to yieldingly resist pulling apart of said handles and to draw said handles together.
- 45 6. A mattress having a pair of opposite walls, each wall being formed with a pair of openings, the openings in one wall being aligned with the openings in the other wall, a handle on each wall having a pair of portions passing through a pair 50 of said pair of openings, and a portion interconnecting said pair of portions, and means extensible a predetermined distance only interconnecting said handles and extending within said mattress, said means including a spring to yieldingly resist extension of said interconnecting means said predetermined distance and to return 55 said interconnecting means to normal condition.
- 55 7. A mattress having opposite side walls, handles on said opposite side walls, each handle comprising a single elongated member having a looped portion and a pair of aligned portions extending outwardly from said looped portion, each side wall being provided with an eyelet through which said looped portion passes, yielding means to draw said handles together, and means to limit separation of said handles.
- 60 8. A mattress having opposite side walls, handles on said opposite walls, each handle having a looped portion and a pair of aligned portions extending outwardly from said looped portion, each side wall being provided with an eyelet through which said looped portion passes, and resilient 65 means interconnecting said looped portions, and portions on the outwardly extending portions of each handle, disposed parallel to one another and passing through openings in a side wall of said mattress.
- 70 9. A mattress having opposite side walls, handles on said opposite walls, each handle having a looped portion and a pair of aligned portions extending outwardly from said looped portion, each side wall being provided with an eyelet through which said looped portion passes, resilient means interconnecting said looped portions, and portions on the outwardly extending portions of each handle, disposed parallel to one another and passing through openings in a side wall of said mattress, and a plate on the inside of said side wall having a slot receiving said looped portion and openings to receive said inwardly extending portions.
- 75 10. A mattress having a pair of opposite side walls, each side wall formed with a pair of openings, a handle on each of said side walls, each handle comprising a member lying against the outer side of one of said side walls and having openings registering with the openings in said side wall, a flexible member within said mattress having outer end portions extending through the openings in said side wall and through the openings in said member, said outer ends being knotted with the knots engaging said member, and means 80 interconnecting the flexible members of the handles on the opposite side walls of the mattress.
- 85 11. In combination, a mattress, handles on opposite sides of said mattress, and means yieldingly 85 extensible to a limited degree, disposed within the mattress and interconnecting said handles.
- 90 12. In combination, a mattress, handles mounted on the side walls thereof and movable from non-projecting to projecting position relative to 90 said side walls, means extensible a predetermined distance only, interconnecting said handles to permit movement of said handles from non-projecting to projecting position, said means including means for yieldingly resisting movement of 95 said handles from non-projecting to projecting position and for moving said handles from projecting to non-projecting position and for holding said handles in non-projecting position, and for yieldingly resisting bulging of said side walls, 100 said interconnecting means becoming a positive tie after said handles have been moved apart said predetermined distance from non-projecting to projecting position, to prevent outward pull on said side walls of said mattress.
- 105 13. In combination, a mattress having opposite side walls, a pair of handles slidably mounted on said side walls, and means within said mattress interconnecting said handles normally holding said handles in contact with said opposite walls 110 and yieldingly resisting separation of said handles and preventing separation of said handles more than a predetermined distance.
- 110 14. In combination, a mattress having opposite side walls, a handle on each wall, and means extending through said mattress and interconnecting said handles for resiliently pressing said handles against said side walls and yieldingly resisting separation of said handles, and including means to limit separation of said handles to a 115 predetermined distance.
- 115 15. In combination, a mattress having opposite side walls, a pair of members on said side walls, one of which comprises a handle, and means within said mattress interconnecting said mem- 120

bers normally holding said members in contact with said opposite walls and yieldingly resisting separation of said members and preventing separation of said members more than a predetermined distance.

5 16. In combination, a mattress having side walls, a pair of members at said side walls, and means extending through the mattress and interconnecting said members, permitting separation 10 of said members to a predetermined amount and preventing separation of said members more than said predetermined amount, at least one of said members comprising a handle on the outside of one of said side walls and movable away from 15 and toward said side wall, and means to yield-

ingly resist movement of said handle away from said side wall.

17. In combination, a mattress having side walls, a handle on a side wall of the mattress, movable toward and away from said side wall, 5 means extending through said mattress and connecting said handle with another side wall to limit movement of said handle to a predetermined amount and to transmit an outward pull on said handle to said other side wall to cause an inward 10 push thereon, and yielding means to hold said handle against said side wall and yieldingly resist movement of said handle away from said wall.

ALBERT M. BANK. 15
